HANGING SHELF

Arthur A. Klepper, Forest Hills, N. Y.

Application October 11, 1949, Serial No. 5,430

Term of patent 14 years

(Cl. D33—3)

To all whom it may concern:

Be it known that I, Arthur A. Klepper, a citizen of the United States, residing in Forest Hills, L. I., county of Queens, and State of New York, have invented a new, original, and ornamental Design for Hanging Shelf, of which the following is a specification, reference being had to the accompanying drawing, forming a part thereof, in which:

Fig. 1 is a top plan view of my new design for hanging shelf;

Fig. 2 is a front elevational view thereof;

Fig. 3 is a rear elevational view thereof, and

Fig. 4 is a vertical cross-sectional view taken along the line 4—4 of Fig. 2.

The dominant features of the design reside in the portion of the drawing shown in full lines.

I claim:

The ornamental design for a hanging shelf, as shown and described.

ARTHUR A. KLEPPER.
